UNITED STATES PATENT OFFICE.

WILLIAM B. REARICK, OF BALTIMORE, MARYLAND.

CHECK-CANCELING ATTACHMENT FOR ADDING-MACHINES.

1,117,602.

Specification of Letters Patent.

Patented Nov. 17, 1914.

Application filed September 11, 1913. Serial No. 789,294.

To all whom it may concern:

Be it known that I, WILLIAM B. REARICK, a citizen of the United States, residing at Baltimore city, State of Maryland, have invented certain new and useful Improvements in Check-Canceling Attachments for Adding-Machines, of which the following is a specification.

This invention relates to stamping or 10 printing attachments for adding or other registering machines, and its object is to provide a device which stamps certain data on checks, bills, etc., as the amounts thereof are put into the machine and registered.

15 The invention also has for its object to provide a novel operating mechanism for the stamping member, said mechanism being connected to the actuating handle of the machine, whereby an impression is made on 20 each check, bill, etc., as the handle is actuated to register the amount of such check, bill, etc.

A further object of the invention is to 25 provide a novel inking device for the stamping member, whereby ink is automatically supplied to said member, the parts being so constructed and connected that the stamping member is normally in contact with the inking device and the latter swings to enable 30 the stamping member to clear the same when it swings to make an impression, after which the stamping member returns to its normal position and the inking device also resumes its normal position.

35 The herein stated objects are attained by a combination and arrangement of parts to be hereinafter described and claimed, reference being had to the accompanying drawings in which—

40 Figure 1 is a front elevation of the device applied to an adding machine; Fig. 2 is a plan view; Fig. 3 is a side elevation; Fig. 4 is a cross-section of the stamping member, Fig. 5 is a perspective view of a detail and 45 Fig. 6 is a rear elevation of the printing device.

Referring specifically to the drawings, 10 denotes an ordinary adding machine having a crank handle 11 the movement of which 50 actuates the mechanism by which the amount or number represented by a depressed key will be accumulated by the registering devices, and a record thereof produced by certain recording devices. As this 55 type of machine is well known, and its struc-

ture is immaterial to the present invention, a detailed description thereof is deemed unnecessary. The stamping or printing attachment to be presently described is operatively connected to the actuating handle 11, 60 and with this exception it is entirely independent of the machine.

In a bracket 12 carried by a base board 13, on which the machine is mounted, is journaled a rock-shaft 14 having crank arms 15 65 and 16, respectively, at its ends. Between the handle 11 and the crank arm 15 is a pitman connection 17, whereby the shaft 14 is rocked when the handle is swung.

From the base board 13 rise standards 18 70 which support rock-shafts 19 and 20, respectively, the former being near the bottom and the latter near the top of the standards. One end of the rock-shaft 19 extends some distance from one of the standards, 75 and said end is supported in a bearing 21 mounted on the base board 13. The last-mentioned end of the rock-shaft 19 has a crank arm 22 which is connected by a pitman 23 to the crank arm 16, by which the 80 motion of the rock shaft 14 is communicated to the rock-shaft 19. Made fast to the rock-shaft 19, by set screws 24 or other suitable means, are two parallel arms 25 which carry a stamping or printing member at their 85 outer ends. The arms 25 swing in a vertical plane toward and from the base board 13 when the shaft 19 is rocked.

The stamping member comprises a base plate 26 carrying a rubber backing plate 27 90 having a type-carrying portion 28. On the back of the base plate 26 are clips 29 which fit slidably over the arms 25 in order that the stamping member may be removed therefrom. The stamping member is locked 95 in place on the arms 25 by a latch, the latter comprising a cross-bar 30 seating in alined notches 31 in the edges of the arms 25 and carried at its ends by flat springs 32 secured to the clips 29. The stamping member is 100 also provided with a date stamp, the same comprising type carriers in the form of endless bands 33 passing over rollers 34 and a backing bar 35. The parts 26 and 27 have parallel slots 36 through which the bands 33 105 extend flush with the type portion 28. The shaft 37 of the rollers 34 is supported in a frame composed of spaced side members 38 connected by a cross bar 39, said frame being secured by fastening its side members to the 110

clips 29. The backing bar 35 is channeled to straddle the narrow strip of the part 27 which lies between the slots 36.

The inking device for the stamping member is an ordinary pad 40 on the back of which are clips 41 which slidably engage the outer portions of angular arms 42 made fast to the rock-shaft 20 by set screws 43 or other suitable means. A cross-bar 44 seating 10 in notches 45 in the arms, and carried by flat springs 46 secured to the clips 41, serves to lock the pad on the arms, and upon disengaging said cross-bar from the notches, the pad may be removed from the arms. The 15 arms are so positioned on the rock-shaft 20 that they normally project horizontally therefrom, with their outer ends, to which the pad is secured, pointing downward, thus holding the pad normally in vertical position. 20

On the rock-shaft 19 is made fast by a set screw 47, or otherwise, an arm 48 having at its outer end a side pin 49 which seats in the longitudinal slot 50 of a lever 51. The 25 pin is free to travel in the slot between stops 52 at one end thereof. In the other end of the slot is slidably mounted a crank 53 which is fast on the rock-shaft 20.

The stamping member and the pad 40 are 30 normally face to face in perpendicular position, the stamping member being in contact with the pad. The arms 25 and 48 are also perpendicular, the arm 48 being alongside one of the arms 25, and the crank 53 being in vertical alinement with the pin 49. If now the handle 11 is swung to actuate the 35 machine, the shaft 19 is rocked through the connections hereinbefore described, whereupon the arms 25 swing down and carry the stamping member to the check, bill or other paper to be marked, as shown by dotted lines in Fig. 3. The arm 48 also swings down, and through the pin 49 swings the lever 51 in a direction to carry its upper end rearward. This movement of the 40 lever, through the crank 53, rocks the shaft 20 in a direction to tilt the pad 40 upward so that the stamping member may clear the same as it swings down. The pin 49 slides 45 down the slot 50 and when it reaches the bottom stop 52 it pulls the lever down, the crank 53 sliding in the slot until it reaches the upper end thereof. The stamping member is now in horizontal position to stamp 50 the check, bill or other paper. On the return stroke of the handle 11, the shaft 19 is rocked to swing the arms 25 and 48 upward, and back to perpendicular position to restore the stamping member and the pad 55 40 to their normal position. As the arm 48 swings upward and the pin 49 reaches the upper stop 52, the lever 51 slides upward, and after the stamping member passes to the front of the pad to perpendicular position, the lever also assumes a perpendicular

position, and then the crank 53 swings the pad back to its normal position facing the stamping member, whereupon the parts are ready for another operation.

The base board 13 has an aperture 54 to 70 accommodate the parts 16 and 23, and also carries a pad or other suitable support 55 on which the checks, bills, or other papers 56 to be stamped are placed.

It will be seen from the foregoing that the 75 invention provides a stamping attachment which is simple in construction and easily operated, the actuation of the crank handle of the adding machine also actuating the attachment. 80

The preferred embodiment of the invention has been shown, but it will be evident that various changes and modifications in the structural details may be made without departure from the spirit and scope of the 85 invention. It is also to be understood that the invention is not limited to adding machines, but may be applied to other registering machines having a crank handle or other movable actuating element. 90

I claim:

1. A stamping mechanism for registering 95 machines, comprising a base, vertically arranged arms pivoted to the rear edge of said base, a stamping member provided with clips adapted for engaging over the ends of said arms, spring held means engaging said arms for locking said stamping member in position, and means for operating said arms.

2. A stamping mechanism for registering 100 machines, comprising a base, vertically arranged arms pivoted to the rear edge of said base, a stamping member provided with clips adapted for engaging over the ends of said arms, means for locking said stamping member in position embodying a spring-held 105 cross bar and notches in said arms, and means for operating said arms.

3. A stamping mechanism for registering 110 machines, comprising a stamping member supported on the ends of pivoted arms, a swinging inking pad pivoted independently of the stamping member, means for operating said stamping member in a direction toward said inking pad, and an additional 115 means operated by the stamping member for swinging said inking pad out of the path of said stamping member.

4. A stamping mechanism for registering 120 machines, comprising a stamping member, a swinging inking device pivoted independently of the stamping member, said stamping member and inking device being normally face to face, swinging supports for the stamping member and the inking device, means for actuating the support of the stamping member, and means for actuating the inking device to swing said device clear of the stamping member. 125

5. A stamping mechanism for registering machines, comprising a stamping member, a swinging inking device pivoted independently of the stamping member, said stamping member and inking device being normally face to face, swinging supports for the stamping member and the inking device, means for actuating the support of the stamping member, and means operated by 5 said actuating means of the stamping member for actuating the support of the inking device to swing said device clear of the stamping member.

10. A stamping mechanism for registering machines, comprising a stamping member, a swinging support for the stamping member, a rock shaft carrying said support, means for operating the rock shaft, an inking device, a swinging support for the inking device, a rock shaft carrying the last-mentioned support, and a connection between the rock shafts for actuating the second-mentioned rock shaft to swing the inking device clear of the stamping member.

15. A stamping mechanism for registering machines, comprising a stamping member, a swinging support for the stamping member, a rock shaft carrying said support, means for operating the rock shaft, an inking device, a rock shaft carrying the last-mentioned support, and a connection between the rock shafts for actuating the second-mentioned rock shaft to swing the inking device clear of the stamping member.

20. A stamping mechanism for registering machines, comprising a stamping member, a swinging support for the stamping member, a rock shaft carrying said support, means for operating the rock shaft, an inking device, a rock shaft carrying the last-mentioned support, and a connection between the rock shafts for actuating the second-mentioned rock shaft to swing the inking device clear of the stamping member.

25. A stamping mechanism for registering machines, comprising a stamping member, a swinging support for the stamping member, a rock shaft carrying said support, means for operating the rock shaft, an inking device, a rock shaft carrying the last-mentioned support, an arm fastened on the first-mentioned rock shaft, and a connection between said arm and the second-mentioned rock shaft to swing the inking device clear of the stamping member.

30. A stamping mechanism for registering machines, comprising a stamping member, a swinging support for the stamping member, a rock shaft carrying said support, means for operating the rock shaft, an inking device, a rock shaft carrying the last-mentioned support, an arm fastened on the first-mentioned rock shaft, and a connection between said arm and the second-mentioned rock shaft to swing the inking device clear of the stamping member.

35. A stamping mechanism for registering machines, comprising a stamping member, a swinging support for the stamping member, a rock shaft carrying said support, means for operating the rock shaft, an inking device, a rock shaft carrying the last-mentioned support, an arm fastened on the first-mentioned rock shaft and carrying a side pin, a crank on the last-mentioned rock shaft, and a lever having a slot in which the side pin and the crank are slidably mounted.

40. A stamping mechanism for registering machines, comprising a stamping member, a swinging support for the stamping member, a rock shaft carrying said support, means for operating the rock shaft, an inking device, a rock shaft carrying the last-mentioned support, an arm fastened on the first-mentioned rock shaft and carrying a side pin, a crank on the last-mentioned rock shaft, and a lever having a slot in which the side pin and the crank are slidably mounted.

45. A stamping mechanism for registering machines, comprising a stamping member, a swinging support for the stamping member, a rock shaft carrying said support, means for operating the rock shaft, an inking device, a rock shaft carrying the last-mentioned support, an arm fastened on the first-mentioned rock shaft and carrying a side pin, a crank on the last-mentioned rock shaft, and a lever having a slot in which the side pin and the crank are slidably mounted.

50. A stamping mechanism for registering machines, comprising a stamping member, a swinging support for the stamping member, a rock shaft carrying said support, means for operating the rock shaft, an inking device, a rock shaft carrying the last-mentioned support, an arm fastened on the first-mentioned rock shaft and carrying a side pin, a crank on the last-mentioned rock shaft, and a lever having a slot in which the side pin and the crank are slidably mounted, and stops in the slot between which the side pin works.

55. A stamping mechanism for registering machines, comprising a stamping member, clips on the base of said member, a support on which the clips are slidably mounted, and a latch for locking the clips on the support.

60. A stamping mechanism for registering machines, comprising a stamping member, clips on the base of said member, supporting arms on which the clips are slidably mounted, said arms having aligned notches, and a spring-supported cross bar carried by the clips and seating in the notches.

65. In testimony whereof I affix my signature in presence of two witnesses.

70. WILLIAM B. REARICK.
